UNITED STATES PATENT OFFICE.

MARK SMITH, OF SOUTH REDDISH, NEAR STOCKPORT, ENGLAND, ASSIGNOR TO
TAYLOR, GARNETT, EVANS & COMPANY LIMITED, OF MANCHESTER, ENGLAND.

BRONZING-MACHINE.

1,157,434.

Specification of Letters Patent. Patented Oct. 19, 1915.

Application filed November 24, 1911. Serial No. 662,116.

To all whom it may concern:

Be it known that I, MARK SMITH, a subject of the King of Great Britain and Ireland, and a resident of South Reddish, near 5 Stockport, England, have invented new and useful Improvements in Bronzing-Machines, of which the following is a specification.

This invention relates to bronzing machines of that type in which the bronze powder is applied by hand by an operative to a printed sheet and in which the sheet with the bronze powder so applied is then polished between suitable burnishing rollers while it is held by the same or another operative.

The objects of my present invention are to so construct and arrange the different parts of such a machine and to so provide them with suitable accessories that the 10 bronze dust is prevented from escaping into the room in which the operatives are working by means of air exhaustion set up in or through such machine, and to provide a single source of power which may be of any 15 suitable type and by means of which both the air exhauster and the burnishing rollers are driven. The air charged with the bronze powder and dust which is withdrawn from the operating parts of the machine may, as 20 is already well known in connection with like exhaustion from other types of bronzing machines, be discharged at any suitable point outside the room or may be discharged 25 into a suitable separator in direct communication with the machine, which separator will effect the separation of the bronze powder from the air and return it to the machine for re-use, the air being permitted 30 to escape.

40 The accompanying drawings illustrate the construction of the improved machine.

Figure 1 shows it partly in front elevation and partly in longitudinal vertical section. Fig. 2 shows it in vertical cross section along 45 the line $x-y$, Fig. 1, certain parts which are in front of the plane of view being indicated in dotted lines. Fig. 3 is a view of a horizontal section taken at irregular heights through the upper part of the machine.

50 The machine comprises a chamber A which extends the full length of the machine above the table B between the two ends C C¹. The upper part of this chamber is formed as a hood D with glass D¹ through

which the operator can see how the work is 55 progressing. The space between the bottom edge D² of the hood and the table B permits the worker's arms to pass into the machine at any point along the table.

E is a shade to prevent reflection of light 60 and thus enable the operator to see clearly through the glass.

From the feed table B¹ which is outside the machine to the left, the operator draws 65 into the left hand part of the machine through a slot C² in the end wall C of the machine a sheet properly prepared to have bronze powder applied to it. The operator takes bronze powder from a suitable receptacle, such for example as the box or drawer 70 F, and applies it to the sheet as is usual. The position of the sheet during the application of the bronze is indicated by the dotted square 2 in Fig. 3; the dotted square 1 indicates the position of the sheet upon the 75 feed table outside the machine. When the bronze has been properly applied the sheet is moved to the right and is passed between the burnishing rollers G G¹. One of its positions during the burnishing operation 80 is indicated by the dotted square 3, Fig. 3. After it has been burnished the sheet is preferably laid on a shelf H forming the floor of 85 a chamber above and behind the burnishing rollers and from which shelf accumulated sheets can be removed when desired through the door H¹.

Air from the workroom is compelled to 90 enter the machine through the whole of the opening which extends along the machine above the front of the table B and this entrance of air prevents dust coming out of such opening into the workroom. The desired air current is set up by the fan J or 95 like air exhauster situated in the back of the machine and driven by the same source of power as drives the burnishing rollers.

K is a suction chamber from which the fan illustrated directly exhausts, and this chamber is in communication with the operative chamber through holes L L¹, and with the chamber in which the burnishing rollers are contained through openings M and trunk N. Any other part of the machine, as for example the chamber in which 100 the finished sheets are placed, may be similarly in communication with the suction chamber through suitable openings and

trunks or the like. The directions of the various air currents are indicated by arrows.

In the machine illustrated the source of power employed is a small electro-motor O mounted directly on the shaft of the centrifugal air fan J. Through suitable gearing P the motion of the fan shaft, properly reduced in speed if necessary, is transmitted 10 to the burnishing rollers.

R indicates an adjusting device of construction well known in connection with burnishing rollers for adjusting them relatively to one another.

15 The electro-motor O may be replaced by any other prime mover, or it may consist of a pulley or other element of gearing driven from outside the machine but similarly adapted to drive both the fan and the 20 burnishing rollers. Whatever the form of motor or driving element employed, there may be inserted at a suitable part of the 25 gearing a clutch or like disconnectible device so that the fan can be started, if desired, without the burnishing rollers commencing to revolve. This disconnectible device may be one of the gear wheels P which may be slidden along its shaft into or out of gear with the burnishing rollers.

30 In the machine illustrated the fan is shown as discharging the air and suspended bronze dust through the pipe S into the centrifugal separator T, from the upper part of which the air escapes while the powder falls to the lower part and is fed to a 35 receptacle F within the machine. This receptacle may be a two compartment drawer F, Fig. 2, the back compartment of which, when in use, comes under the discharge 40 opening of the separator. When this back compartment is filled from the separator,

the drawer is withdrawn and reversed, the original front and empty compartment being put under the separator to be filled, while the now full and front compartment 45 is being emptied by the operator. When the operator has emptied the front compartment and used up any further excess of powder required while the back compartment is filling, the drawer is again reversed 50 and this operation is repeated.

I claim:

A bronzing machine comprising an in-55 closed chamber, a table extending across the front lower portion of said chamber upon which the bronze is adapted to be applied by hand to a flat sheet, power actuated burnishing rollers in another part of said chamber adjacent to but behind said table, a feed table positioned exteriorly of said chamber 60 and adjacent one end wall thereof, said end wall having a slot therein through which a flat sheet may be drawn into the chamber, said front wall of said chamber having a longitudinally disposed opening therein extending 65 the length of the chamber and of dimensions to permit the arms of the operative to enter to manipulate the sheet within the chamber; a transparent top for a part of said chamber providing a sight opening 70 through which the operative may observe the work within the chamber, an air suction device in communication with said chamber, and means for driving said air suction device and burnishing rollers. 75

In witness whereof I have hereunto set my hand in the presence of two subscribing witnesses.

MARK SMITH.
